(57) **CLAIM**

The ornamental design for a sandal, as shown and described.

DESCRIPTION

1. Sandal

1.1 is a perspective view of a sandal showing a new design;

1.2 is a front view thereof;

1.3 is a rear view thereof;

1.4 is a side view thereof;

1.5 is an opposite side view thereof;

1.6 is a top view thereof; and

1.7 is a bottom view thereof.

The reproductions of design n. 1 show only the right shoe, the left shoe is omitted because it is symmetrical to the right shoe; in the figures the dotted lines represent seams.
